UNITED STATES PATENT OFFICE.

DAVID HINDAHL, OF CHICAGO, ILLINOIS.

DUMP-CAR CONSTRUCTION.

Application filed January 29, 1923. Serial No. 615,471.

To all whom it may concern:

Be it known that I, DAVID HINDAHL, a citizen of the United States, residing at Chicago, in the county of Cook and State of Illinois, have invented certain new and useful Improvements in Dump-Car Constructions, of which the following is a specification.

The present invention relates to dump car construction.

More particularly the present invention relates to the type of dump car having a hopper provided with doors adapted to open with a rapid movement. The present invention will be described with reference to the well known type of dump car in which co-operating doors are adapted to form a hopper, said doors meeting along a line lying substantially in the longitudinal central vertical plane of the car.

An object of the present invention is to provide operating mechanism for the dump doors which will combine efficiency of operation with safety for the operator.

A further object is to provide dump door operating mechanism which will permit the doors to dump with a substantially instantaneous movement but which will involve no danger for the operator.

A further object is to provide dump door operating mechanism involving chain or other flexible means which will be free of the objection sometimes encountered that the flexible means becomes entangled with the other mechanism of the car.

Further objects will appear as the description proceeds.

Referring to the drawings—

Figure 1 is a view taken longitudinally of the car, the center portion being broken away to illustrate the two ends of the hopper portion of said car;

Figure 2 is a view, partly in section, of the structure shown in Figure 1, said Figure 2 illustrating the mechanism as seen by an observer looking in the direction of the arrow 2 of Figure 1;

Figure 3 is a view taken along the plane marked by the line 3—3 of Figure 2; and

Figure 4 is a view, partly in section, of the structure shown in Figure 1, said Figure 4 illustrating the mechanism as seen by an observer looking in the direction of the arrow 4 of Figure 1.

Figure 5 is a view taken along the plane marked by the line 5—5 of Fig. 4.

The numerals 10—10 indicate the sides of the car, while the numerals 11—11 indicate the center sills of said car. The numerals 12 and 13 indicate hopper doors, which are pivoted along the longitudinal axes 15 and 16 respectively. Said hopper doors 12 and 13 are shown in their closed positions in full lines in Figures 2 and 4 and in open position by dotted lines in said figures. Said hopper doors are controlled by two transverse shafts 17 and 18.

Referring first to the structure shown at the left-hand end of Figure 1, which structure is illustrated at other angles in Figures 2 and 3, it will be noted that the hopper door 13 is provided with the crank 19. Said crank 19 is mounted upon the journal 20, which is mounted in a suitable bearing in an axis distant from the pivotal axis 16. Said crank 19 may consist of two parallel side members 21 and 22, which are mounted in spaced relation upon journal 20 and pin 23. A shaft 23' extends the length of hopper door 13 and has the crank 19 non-rotatably mounted thereon. For the purpose of non-rotatably supporting the crank 19, the shaft 23' may have a squared portion mounted within a square hole in the journal 20 of crank 19. Mounted between the two side members 21 and 22 of the crank 19 is the link 24, which may take an angular form as illustrated in the drawing. The numeral 25 indicates a bearing pin, the numeral 26 a chain guard, and the numeral 27 a pivot pin. The bearing pin 25 forms a bearing for sheave 30 and also carries one end of the guard member 26, the other end of said guard being carried by the pivot pin 27. Said pivot pin 27, pivotally connects link 24 with dump door 12. A chain 31 is connected at one end to the pin 31' and at its other end is connected to the shaft 17 by any suitable attaching means 32. The chain 31 should be of sufficient length to permit the dump doors 12 and 13 to assume their open position, as indicated in dotted lines in Figure 2. To move said dump doors 12 and 13 to closed position, the chain 31 is wrapped upon shaft 17, as indicated in Figures 2 and 3.

Referring to the structure at the right-hand end of Figure 1, which structure is illustrated at other angles in Figures 4 and 5, it will be noted that a link 33 is pivotally connected to the dump door 13 on the pivot pin 34 located in an axis distant from the

pivotal axis 16. The link 33 may take the angular form illustrated in the drawing. Connected to the door 12 on the journal 35 is the crank 36, which may consist of the two side members 37 and 38. Said journal 35 may be non-rotatably mounted upon the shaft 23'. Said side members 37 and 38 may be spaced apart upon the bearing 35 by any suitable means and are spaced apart 10 at their outer ends by the end of the link 33. Said link 33 and side members 37 and 38 may be rotatably connected together by means of the pivot pin 39.

A chain 40 is provided, one end of which 15 is connected to the transverse shaft 18 by any suitable attaching means 41. The other end of said chain 40 may be connected to the framework of the car by any suitable attaching means 42. Said chain 40 forms 20 a loop underlying the crank 36 and link 33 when the dump doors are in closed position and has the function of tripping the dump door mechanism, whereby the car may be dumped with a practically instantaneous 25 motion. The loop of chain 40 has been illustrated as lying in a plane substantially longitudinally of the car, which is substantially transverse to the general direction of link 33 and crank 36.

30 When the dump doors are in closed position as illustrated in full lines in Figures 2 and 4, the weight of the lading within the car will tend to force bearings 23', 27, 34 and 39 downwardly, which action in cooperation with the cranks 19 and 36 will tend 35 to force the dump doors together and hold same closed. When it is desired to cause the dumping of the car, the shaft 18 will be rotated to shorten the loop of chain 40, 40 thereby raising crank 36. Raising of crank 36 will result in the clockwise rotation of shaft 23' as viewed in Figure 4, which is a counter-clockwise rotation as viewed in Figure 2. By reason of the non-rotatable 45 connection of cranks 19 and 36 with shaft 23', crank 19 will be rotated at the same time that crank 36 is rotated. When pivot means 39 and 23 have been raised above dead center, the practically instantaneous opening 50 of the dump doors 12 and 13 will result. The opening movement of dump doors 12 and 13 will exert a pull upon chain 31 and will cause said chain to rotate shaft 17, whereby said chain will become unwrapped from said shaft 17 and will assume the position indicated in dotted lines in 55 Figure 2.

When it is intended to close the dump doors, the shaft 17 will be rotated which 60 action, by reason of the engagement of chain 31 with sheave 20, will draw the dump doors 12 and 13 to closing position. Movement of the dump doors 12 and 13 will cause the links 24 and 33 to assume the positions 65 illustrated in Figures 2 and 4. In moving

from the dotted line position shown in Figure 4 to the full line position shown in said figure, the ends of crank 36 and link 33 which are connected together will move within the loop provided by chain 40, 70 whereby the parts are located for tripping action when the shaft 18 is again rotated for dumping functions.

By reason of the fact that separate shafts are provided for closing the dump doors and for causing the opening thereof, the necessity for special safety devices is rendered unnecessary. It will be clear that the operating shafts 17 and 18, instead of being located at opposite ends of the dump doors, 75 may be located adjacent to one end thereof. The illustrated construction is preferred, however, for the reason that simplicity of construction and operation are secured by said arrangement. 80

By reason of the fact that the releasing chain 40 is arranged in a loop adapted to underlie the operating crank 36, there is a minimum chance of interference of the chain 40 with the operating parts of the car. 90 This construction is simple and is very little liable to get out of order in service.

One embodiment of the present invention has been described in detail. Many modifications will occur to those skilled in the art. 95 It is intended in this patent to cover all such modifications that fall within the scope of the invention as defined by the appended claims.

What is claimed is:

1. Dump car construction comprising a pair of dump doors, a pair of rotatable shafts, said dump doors being provided with link mechanism for locking same in closed position and permitting the practically instantaneous opening thereof, one of said shafts being provided with flexible means for operating said doors to close same and move said link mechanism to holding position, and the other of said shafts being provided with means for operating said link mechanism to cause said doors to move to open position. 100

2. Dump car construction comprising a pair of doors, a pair of mechanisms operatively associated with said doors, each of said mechanisms comprising a crank and a link co-operating to hold said doors closed under the influence of gravity, said cranks being constrained to operate in unison, flexible means located at one end of said doors for raising one of said cranks against the influence of gravity and flexible means located at the other end of said doors for raising said doors. 115

3. Dump car construction comprising a pair of doors, a pair of mechanisms operatively associated with said doors, each of said mechanisms comprising a crank and a link co-operating to hold said doors closed 120

under the influence of gravity, said cranks being constrained to operate in unison, flexible means located at one end of said doors for raising one of said cranks against the influence of gravity, and flexible means located at the other end of said doors for moving said doors to closed position and said mechanisms to door holding position.

4. Dump car construction comprising
10 dump door means, link mechanism operatively associated therewith adapted to occupy a position in which it exerts forces under the influence of gravity for holding said door means closed, and a flexible member
15 lying in a plane transversely of said link mechanism adapted to enclose a portion of said link mechanism and upon operation of said flexible member to raise said link mechanism against the force of gravity
20 to cause the opening of said door means.

5. Dump car construction comprising dump door means, link mechanism extending transversely of the car adapted when in a predetermined position to hold said door
25 means closed under the influence of gravity, and a flexible member having a loop extending transversely of said link mechanism adapted to raise said link mechanism against the force of gravity to cause the rapid
30 opening of said door means.

6. Dump car construction comprising dump door means, a pair of operating mechanisms therefor, said mechanisms having parts constrained to move in unison, each of
35 said mechanisms comprising links for urging said door means to closed position under the influence of gravity, and a pair of flexible members, one of which is operative to move said door means to closed position and the other of which is adapted to control
40 said mechanisms to raise same against the force of gravity to cause the opening of said door means, said last mentioned flexible member including a loop adapted to be lengthened or shortened, said loop under-
45 lying one of said link mechanisms and adapted to trip said mechanism upon the shortening of said loop.

7. Dump car construction comprising
50 dump door means, a pair of operating mechanisms therefor, said mechanisms having parts constrained to move in unison, each of said mechanisms comprising links for urging said door means to closed position
55 under the influence of gravity, and a pair

of flexible members, one of which is operative to move said door means to closed position and the other of which is adapted to control said mechanisms to raise same against the force of gravity to cause the
60 opening of said door means, said latter mentioned flexible member including a loop lying in a plane transverse to its corresponding link mechanism and being adapted to operate its said link mechanism against the
65 force of gravity to trip said door means.

8. Dump car construction comprising dump door means, operating mechanism therefor, said mechanism comprising means for urging said door means to closed position under the influence of gravity, and a pair of flexible members, one of which is operated to move said door means to closed position and the other of which is adapted to control said mechanism to raise same
70 against the force of gravity to cause the opening of said door means, said other flexible member comprising a loop lying substantially in a plane extending longitudinally of the car.
80

9. Dump car construction comprising dump door means, mechanism for controlling the closing and the practically instantaneous opening thereof, said mechanism including a crank and a link operatively associated with said door means, flexible means for raising said mechanism against the force of gravity to a position to hold said door means closed, and flexible means adapted to operate said mechanism against
90 the force of gravity to cause the practically instantaneous opening of said door means, said last mentioned flexible means comprising a loop adapted to underlie said crank transversely thereof.
95

10. Dump car construction comprising dump door means, mechanism operative under the influence of gravity when in a predetermined position to hold said door means closed, and a flexible member having a loop portion hanging substantially longitudinally of the car and underlying said mechanism, and means for controlling the dimensions of said loop portion to raise said mechanism against the force of gravity
100 to cause the rapid opening of said door means.

Signed at Chicago, Illinois, this 15th day of December, 1922.

DAVID HINDAHL.
